H. C. Karel.

ATTORNEY.

UNITED STATES PATENT OFFICE

2,018,543

BEER TAPPING MECHANISM

William Buirk, St. Bernard, Ohio

Application October 12, 1933, Serial No. 693,329

2 Claims. (Cl. 225—3)

My invention relates to a new and useful mechanism for dispensing draught beer and provides a safety device in connection therewith, as well as providing means for returning the liquid in the coil to the barrel or other container when it is desired or necessary to clean the coils.

Under present conditions it is necessary to clean the coil leading from the barrel to the dispensing faucet at frequent intervals. Such cleaning is often necessary while the container or barrel contains a portion of the fluid being dispensed therefrom. In the present method the valve near the barrel is closed and the coil disconnected above the valve and the liquid in the coil drained therefrom into an open vessel. This liquid unless used immediately becomes stale and is entirely wasted. In my improved mechanism I provide means for returning the liquid in the coil to the barrel prior to disconnecting the coil from the tapping device, whereby the coil can be cleaned at any time regardless of the amount of liquid in the barrel and without the necessary loss of fluid.

The object of my invention is to provide a valve in the air line to the tap which is so constructed to permit closing of the air inlet and outlet ports; or to provide an uninterrupted free passage of air through the valve; or to provide a free passage of air through the valve with a safety valve in conjunction therewith to relieve any excess pressure from being applied to the contents of the barrel; or to provide closing of the inlet port and maintaining a limited pressure on the contents of the barrel; or to provide closing of the inlet and safety valve ports and forming an open connection between the outlet port and a port exposed to the atmosphere to permit venting of the barrel when so desired. A further object is to provide means for disconnecting the air line from the valve whereby a suitable water thief can be attached thereto to make connection with the dispensing faucet for applying pressure to the liquid in the coil through the dispensing faucet.

My invention will be further readily understood from the following description and claims and from the drawings, in which latter:

Fig. 1 is a side elevation of my improved device, in connection with a beer tapping mechanism, being partly broken away.

Fig. 2 is a longitudinal section view of the tap and my improved valve.

Fig. 3 is a detail section of the valve, taken in the plane of the line 3—3 of Fig. 2.

Fig. 4 is a side view of my improved valve, and

Figs. 5, 6, 7 and 8 are detail sectional views showing the various positions of the valve for accomplishing various results.

Beer or other beverages which are contained in barrels or casks are usually cooled by means of a

coil extending either through or about a suitable refrigerant whereby the beverage passing from the barrel to the dispensing faucet passes through the cool coils for serving the beverage cold. Many beverages leave deposits in the coil which require periodic cleaning in order that clear untainted beverage may be served.

The cask or barrel containing the beverage is usually located either in the basement or at a point below the dispensing faucet which requires a pressure to be applied to the head of the liquid for forcing the liquid up to the dispensing faucet. The usual construction now being employed for the purpose of tapping the barrel comprises a tap 11 having suitable means for locking the tap to the barrel as indicated at 12. This tap has an air inlet opening 13 and a draft tube 14 extending through the tap and down into the barrel 15. The tube 14 is locked to the tap as indicated at 18 for sealing the tube to the tap. A valve 16 is usually inserted between the tube 14 and the coil 17, forms a connection between the coil and the tube and also permits shutting off the supply of liquid in the barrel. The liquid in the barrel is forced up through the tube 14 by air pressure received through the inlet 13 and down around the tube 14 to the head of the liquid. The parts thus far described are in usage at the present time and I do not wish to confine myself to their particular construction as any suitable tapping device can be used with my improved mechanism wherein air under pressure is applied to the head of liquid in the container. Under present conditions, when it is desired to clean the coil, the air to the opening 13 is shut off and the valve 16 closed to prevent the liquid from passing up through the tubes but considerable liquid remains in the coil which is often seventy-five or a hundred feet in length which when disconnected from the valve 16 is drained from the coil and is usually a complete loss to the proprietor.

My invention contemplates means for overcoming this loss by providing an auxiliary valve in the air line as indicated at 20 whereby when it is desired to disconnect the coil for purposes of cleaning the same, the beverage in the coil can be returned to the cask without the incident loss as by the old method. To accomplish this I provide the valve 20 with a suitable inlet port 21 and an outlet port 22. There are suitable connections on each end of the valve for connecting the valve to the usual air line 23 which supplies air or gas under pressure from either a suitable compressor or from a tank of carbonated gas and to the tap. Extending outward from the air inlet port is a tubular housing 24 arranged to receive a suitable check valve 25 therein and having threads on the outer circumference thereof for receiving a suitable coupling nut 26 for securing the air line 23 to the valve housing. Extending outwardly from

the outlet port 22 is a suitable threaded portion 27 arranged to be received in a threaded projecting extension 28 of the tap 11.

- 5 The valve housing is provided with a tapered bore 29 in which a valve plug 30 is received and suitably held therein by means of a nut 31 received over a threaded end 32 of the plug. The plug is provided with suitable openings 33, 34 and 35 all of these openings being interconnected for permitting air to pass from one opening of the valve. Besides the ports 21 and 22 in the valve housing there are also ports 36 and 37. Port 36 connects with a suitable safety valve 38 received in a tubular extension of the housing 20 and being held in contact with its seat by means of a spring 39 interposed between the valve and a threaded plug 40. The plug 40 is provided with a central opening 41 of slightly larger diameter than the stem 42 of the valve whereby upon opening of the valve 38 the air or gas will escape through the opening 41. The port 37 provides a quick relief of the air or gas in the barrel, being open directly to the atmosphere.
- 25 The valve plug 30 is provided with a suitable handle 43 and a pointer 44 for indicating and turning the valve to the various positions for setting up the valve to accomplish various results. In this connection, I have provided five positions 30 of the valve for various results. In the position shown in Fig. 2 both the inlet and outlet ports are closed preventing additional pressure being applied to the contents of the barrel and also preventing escape of the air or gas in the barrel.
- 35 When the valve is in this position the pointer 44 will register with a mark 50 on the edge of the valve. The valve in this position permits uncoupling of the coupling 26 for removing the air line from the valve in the event it is desired to 40 repair or replace the air line. When the valve is turned to the position shown in Fig. 5, the pointer 44 will register with a mark 51 on the face of the valve which provides a free passage of air under pressure from the port 21 through 45 the port 22 to the barrel with the openings 33 and 34 making connection between the ports 21 and 22. It will be noted that in this position the ports 36 and 37 are closed.
- 50 Under certain conditions it is desirous of having a safety valve in the connection to the barrel, whereby only a limited pressure can be applied to the contents of the barrel. When this condition exists the valve is turned with the pointer 44 registering with the mark 52 on the valve in 55 which position the valve will be as shown in Fig. 6, which permits the flow of air under pressure from the port 21 to the port 22 and to the barrel. The opening 35 also forms a connecting opening with the port 36 which has the safety valve 38 in the outlet of this port. By adjusting the nut 40 any suitable pressure can be applied to the valve 38 whereby the valve will only open when the pressure in the container exceeds the pressure for which the valve is set. In beer dispensing arrangements wherein electrical refrigeration is used the coil often is placed in direct contact with the cooling coils of the refrigerating plant, which often causes the liquid in the coil to freeze, thus preventing dispensing of the liquid from the barrel. With the valve set in the position shown in Fig. 6 when such a condition arises any additional pressure being applied to the contents of the barrel will be relieved through the valve 38

thus preventing undue pressure being applied to the coils which might tend to burst the same.

With the valve turned to the position shown in Fig. 7 the pointer 44 registers with a mark 53 on the valve closing the inlet port 21, port 37 and 5 forming a connection between the port 22 and the port 36. With the valve in this position the safety valve is set to a limited pressure and the beer in the coil can be forced through the coil by means of a suitable hand pump attached to 10 the dispensing faucet, or by means of a separate air line for creating a pressure on the beer in the coil for driving the beer back into the barrel. In some arrangements it may be more convenient to disconnect the coupling 26 and attach a suitable coupling thereto for forming a connection with the dispensing faucet 54 whereby pressure can be exerted on the liquid in the coil through the dispensing faucet for forcing the liquid in the coil back to the barrel while maintaining a lighter 20 pressure on the contents of the barrel. Any increase in pressure within the barrel will be relieved through the safety valve 38.

When it is desired to free the contents of the barrel of all the pressure the valve is turned to 25 the position shown in Fig. 8 wherein the pointer 44 will register with a mark 55 on the valve housing for forming a connection between the ports 22 and 37 and closing the ports 21 and 36. This connection between the ports 22 and 37 permits 30 all pressure on the liquid to escape to the atmosphere. In some arrangements of beer dispensing equipment with this pressure relieved and opening the dispensing faucet 54 the liquid in the coil will flow by gravity back to the container. In the 35 event that the arrangement is such as to prevent the liquid from returning by the force of gravitation, coupling 26 can be removed from the valve housing, a suitable coupling attached thereto and attached to the dispensing faucet 54 for forcing 40 the liquid down through the coil, or by means of a hand pump or separate air line.

I have described the various positions of the valve and the means employed for returning the liquid in the coil to the barrel or cask. After this 45 liquid has been returned to the barrel the valve 16 is closed and the coil disconnected above the valve whereby it can readily be cleaned by any suitable method without the loss of any of the beverage.

Having thus fully described my invention, what I claim as new and desire to secure by Letters Patent, is:

1. In a beer tapping mechanism, the combination of a tap, an air inlet in said tap, a valve housing connected to said air inlet, an air line having connection with said housing, a passage through said housing, a valve plug in said passage, inlet and outlet ports in said housing, auxiliary ports in said housing about said valve plug, one of said 60 ports open to the atmosphere and the other provided with a safety valve, an opening in said valve plug for connecting a plurality of ports and means for operating said valve.

2. A valve comprising a housing, a central opening through said housing, a valve plug in said opening provided with a plurality of passages, a plurality of ports in said housing about said valve plug, said passages connecting said opening with said valve plug, a safety valve in one of 70 said ports and means for connecting any pair of said plurality of ports.

WILLIAM BUIRK.
